UNITED STATES PATENT OFFICE.

CECIL ARTHUR HUBBARD, OF ANN ARBOR, MICHIGAN.

SAFETY DEVICE FOR RAZORS.

1,285,188.

Specification of Letters Patent. Patented Nov. 19, 1918.

Application filed March 26, 1918. Serial No. 224,844.

To all whom it may concern:

Be it known that I, CECIL A. HUBBARD, citizen of the United States, residing at Ann Arbor, in the county of Washtenaw and State of Michigan, have invented certain new and useful Improvements in Safety Devices for Razors, of which the following is a specification.

This invention relates to an improved safety attachment for straight blade razors and has as its primary object to provide a device of this character which may be readily attached to razors of the character indicated already in use for preventing accidental cutting of the face in the operation of shaving.

The invention has as a further object to provide a device of the above described character employing a series of guard fingers at each side of the razor blade and wherein the said series of fingers may be adjusted so that, in the operation of shaving, one series of fingers will contact with the face below the cutting edge of the blade while the other series of fingers will contact the face above the said cutting edge to consequently minimize the possibility of accidental cutting of the face.

The invention has as a still further object to provide an arrangement wherein each series of guard fingers will be carried by a finger bar and wherein the fingers may be individually adjusted upon the finger bars so that the free ends of the series of fingers may be positioned to conform to any irregularities in the cutting edge of the razor blade.

And a still further object of the invention is to provide an improved arrangement for rigidly holding the finger bars in their elevated or lowered position with respect to the razor blade to consequently rigidly support the fingers to contact with the face in the operation of shaving.

Other and incidental objects will appear as the description proceeds, and in the drawings wherein I have illustrated the preferred embodiment of the invention and wherein similar reference characters designate corresponding parts throughout the several views:

Figure 1 is a side elevation showing my improved attachment applied to a conventional type of straight razor blade.

Fig. 2 is a perspective view showing the supporting frame of the device in detail,

Fig. 3 is a perspective view showing one of the guard finger bars in detail,

Fig. 4 is a vertical sectional view taken on the line 4—4 of Fig. 1 and particularly illustrating the construction of the attaching yoke employed for securing the frame of the device to the razor blade,

Fig. 5 is a sectional view taken on the line 5—5 of Fig. 1 and particularly showing the mounting of the arms employed for locking the guard finger bars in their raised or lowered position with respect to the razor blade,

Fig. 6 is a sectional view taken on the line 6—6 of Fig. 1 and particularly illustrating the mounting of the guard finger bars at their inner ends,

Fig. 7 is a sectional view showing the manner in which the series of guard fingers are adjusted with respect to the razor blade in the operation of shaving,

Fig. 8 is a sectional view taken on the line 8—8 of Fig. 1 and particularly showing the mounting of the guard finger bars at their outer extremities, and

Fig. 9 is a perspective view showing one of the guard fingers in detail.

In order that the construction, mounting and operation of my improved safety device may be accurately understood, I have, in the drawings, shown the said device in connection with a conventional type of straight blade razor 10 having a reduced shank 11. In carrying out the invention I employ a substantially U-shaped frame including parallel arms 12 at the inner extremities of which are formed laterally and outwardly directed sleeves 13. At the inner sides of the sleeves the confronting faces of the arms are roughened or formed with teeth 14. Projecting forwardly from the bight of the frame is a squared lug 15. The frame is, as particularly shown in Fig. 1 of the drawings, of a length to embrace the razor blade 10 to extend longitudinally thereof with the blade received between the arms of the frame and connecting the frame with the blade is a substantially U-shaped attaching yoke 16. This yoke is formed with suitable resilient arms 17 which embrace the shank 11 of the blade and slidably receive the sleeves 13 of the frame to confront opposite sides of the said shank. The teeth 14 of the arms of the frame are thus disposed to bear against the shank and connecting the free ends of the arms 17 of the yoke is a

105
110

clamp screw 18 which may be adjusted for tightly clamping the inner ends of the arms of the frame against the shank of the blade and thus securely connecting the frame therewith. As will be seen, the sleeves 13 may be shifted longitudinally of the arms 17 of the yoke for adjusting the frame toward or away from the cutting edge of the blade, and threaded through the said sleeves 10 to engage the yoke arms are set screws 19 for holding the frame at adjustment.

Mounted upon the lug 15 of the frame is a depending arm or head piece 20 having a suitable socket formed therein to receive the 15 lug and connected with the said lug by an axial clamp screw 21. As particularly shown in Fig. 8, this arm or head piece is preferably tapered toward its lower end. Riveted or otherwise secured to the arms 12 20 of the frame adjacent their inner extremities are oppositely disposed depending arms 22. These arms are formed with slots 23 while the head piece or arm 20 is formed with similar slots 24. Slidably engaged at their 25 ends in these slots and thus supported by the arms at opposite sides of the razor blade, are longitudinally disposed finger bars 25 and mounted upon each of these bars is a series of guard fingers 26, one of the said 30 fingers being shown in detail in Fig. 9 of the drawings. These fingers are each formed with a laterally enlarged base 27, the inner face of which is, as particularly shown in Fig. 5 of the drawings, slightly convex to 35 conform to one of the concave faces of the razor blade and rising from the outer face of the said base is a laterally directed finger body 28. This finger body is substantially triangular in general contour, being tapered 40 from its upper end toward its lower end and is thus formed with an outer inclined edge 29. At its lower end the finger body projects below the base and is slightly reduced or cut away upon its inner edge as shown at 30 to 45 provide a clearance way for the razor blade. Projecting laterally from the opposite sides of the finger body to confront the base 27 in substantially parallel relation thereto, are oppositely directed flanges 31 and formed 50 through the finger body between the said flanges and the base is a slot 32 extending longitudinally of the finger body. The fingers 26 as thus described are threaded upon the finger bars which are freely received 55 through the slots 32 of the said fingers to support the fingers with the inner curved faces of their bases 27 lying against the opposite side faces of the razor blade. Thus, the bases 27 of the fingers will abut each 60 other for spacing the finger bodies 28 longitudinally of the finger bars while the flanges 29 of the said fingers will overlie the said bars to seat against the outer faces thereof. Threaded into the finger bars to 65 engage the confronting flanges of adjacent

fingers as well as to engage the outermost flanges of the terminal fingers, are a plurality of set screws 33 adjustable to firmly clamp the fingers in position upon the said bars. Consequently, it will be seen that 70 since the slots 32 in the finger bodies are of a length greater than the width of the finger bars, the fingers may be adjustably shifted vertically with respect to the said bars and locked at adjustment by the set screws 33. 75 Therefore, the fingers of each series may be individually adjusted upon the finger bar therefor for positioning the lower ends of the fingers of such series in alinement, as shown in Fig. 1, to conform to a straight 80 cutting edge of a razor blade or otherwise disposed with respect to each other to conform to an irregular cutting edge. The fingers are, of course, arranged with their smaller ends presented downwardly so that 85 the inclined edges 29 of the finger bodies will thus slope in a direction downwardly and inwardly toward the razor blade while below the bases of the fingers, the blade will be received within the clearance ways 30 at 90 the reduced lower ends of the fingers so that the said fingers will at no time contact with the cutting edge of the blade to cause injury thereto.

Mounted upon the arms 12 of the frame 95 medially with respect to the finger bars are swinging catch members for the finger bars. These catch members each include a shank 34 at the outer end of which is formed a laterally and inwardly directed terminal 35. 100 Formed on the inner end of such shank is a split bearing sleeve or loop 36 embracing one of the arms 12 of the frame and mounted to rotate upon a suitable reduced portion 37 formed on the said arm and rounded to receive the sleeve. The sleeve will thus be held against longitudinal movement. Projecting from the upper side of the sleeve is an up-standing lug 38 and fitted through the sleeve at its outer side is a horizontally arranged finger pin 39. As particularly shown in Fig. 5 of the drawings, the catch members are of such length that the terminals 35 thereof may be engaged beneath the finger bars 25 for supporting the said bars in elevated position at the tops of the slots 23 and 24 of the arms 20 and 22 of the supporting frame and consequently holding the guard fingers in retracted position, and mounted upon the top edges of the arms 12 of the 110 frame are leaf springs 40 engaging with the lugs 38 of the catch members for constantly urging the free ends thereof toward the finger bars to engage therewith. The springs 40 are, at their inner ends, screwed or otherwise secured to the arms 12 and are given a half turn to yieldably bear at their outer ends against the inner sides of the lugs to thus yieldably hold the catch members in 115 normally active position. Formed in the up- 120 125 130 135

per edges of the finger bars and adapted to receive the terminals 35 of the catch members, are notches 41.

Normally the finger bars 25 will be engaged above the terminals 35 of the catch members when the guard fingers will thus be locked in retracted position so that the cutting edge of the razor blade will be easily accessible to be kept in thoroughly 10 clean condition. However, when it is desired to use the razor the finger pin 39 of one of the catch members is grasped and such catch member swung outwardly to free the guard finger bar at the adjacent side 15 of the razor blade. This bar will then immediately drop down to the bottoms of the slots 24 and 25 receiving the ends of the bar when the guard fingers of the bar will be supported thereby projecting, as shown in 20 Fig. 7 of the drawings, below the cutting edge of the razor blade. Upon the release of the said catch member, its spring 40 will immediately swing such member to engage the terminal 35 thereof in the notch 41 of 25 the lowered finger bar for thus locking the guard fingers of the bar in extended position. The razor is then ready for use and when applied to the face in usual tilted position, as shown in Fig. 7, it will be noted 30 that the beveled edges 29 of the bodies of the fingers at the inner side of the blade will be disposed to contact with the face above the cutting edge of the blade while the lower ends of the bodies of the fingers at the outer 35 side of the blade will be disposed to contact with the face below the cutting edge of the blade. Thus, the guard fingers will be adapted to contact with the face both above and below the cutting edge of the 40 blade so that possibility of accidental cutting of the face in the operation of shaving will be reduced to a minimum. It will, of course, be understood that either series of 45 guard fingers may be extended, as desired, so that either side of the razor may be disposed adjacent the face and in this connection it will be noted that the catch members employed in connection with the guard finger bars 25 not only provide a means for supporting the said bars in elevated position to 50 lock the guard fingers retracted but also provide a means for locking the bars in lowered position with the guard fingers extended.

It will, therefore, be seen that I provide 55 a particularly efficient construction for the purpose set forth and a safety device which may be readily connected to and used upon substantially any conventional type of straight blade razor. Furthermore, the device is of a very simple nature so that it 60 may accordingly be produced at minimum cost.

Having thus described the invention, what is claimed as new is:

1. A device of the character described in-

cluding a supporting frame, means for connecting the frame with the blade of a razor to extend longitudinally of the said blade, a longitudinal guard finger bar slidably supported by the frame, a series of guard 70 fingers carried by the bar, and means pivoted upon the frame to coact with said bar for locking the bar in elevated position with the guard fingers retracted or locking the bars in lowered position with the guard 75 fingers extended.

2. A device of the character described including a supporting frame having spaced arms joined by a connecting portion, means engaged with the free ends of said arms for 80 connecting the frame with the blade of a razor with the arms extending at opposite sides of the blade longitudinally thereof and with the said connecting portion extending around the outer end of the blade, longitudinal guard finger bars slidably supported from said arms, a series of guard fingers carried by each of said bars and adapted to confront opposite sides of a razor blade, and means upon the frame adapted to coact 85 with said bars for locking the bars in elevated position with the guard fingers retracted or locking the bars in lowered position with the guard fingers extended.

3. A device of the character described including a supporting frame, means for connecting the frame with the blade of a razor to extend longitudinally of the said blade and having the frame engaged therewith for adjustment toward or away from the cutting edge of the blade, a longitudinal guard finger bar slidably supported by the frame, a series of guard fingers carried by the bar, and means upon the frame adapted to coact 100 with said bar for locking the bar in elevated position with the guard fingers retracted or locking the bar in lowered position with the guard fingers extended.

4. A device of the character described including a supporting frame having spaced 110 arms, a yoke for connecting the frame with the blade of a razor to extend longitudinally of the said blade with the arms of the frame disposed at opposite sides of the blade, the said yoke being formed with arms engaging 115 with the arms of the frame, clamping means connecting the arms of the yoke, a longitudinal guard finger bar slidably supported by the frame, a series of guard fingers carried by the bar, and means upon the frame 120 adapted to coact with said bar for locking the bar in elevated position with the guard fingers retracted or locking the bar in lowered position with the guard fingers extended.

5. A device of the character described including a supporting frame, means for connecting the frame with the blade of a razor to extend longitudinally of the said blade, a longitudinal guard finger bar slidably sup- 130

ported by the frame, a series of guard fingers carried by said bar and individually adjustable thereon, and means upon the frame adapted to coact with said bar for locking the bar in elevated position with the guard fingers retracted or locking the bar in lowered position with the guard fingers extended.

5 9. A device of the character described including a supporting frame, means for connecting the frame with the blade of a razor to extend longitudinally of the said blade, a longitudinal guard finger bar supported by the frame, and a series of guard fingers mounted upon the said bar and individually adjustable thereon.

10 10. A device of the character described including a supporting frame, means for connecting the frame with the blade of a razor to extend longitudinally of the said blade, a longitudinal guard finger bar supported by the frame, a series of guard fingers carried by the bar and each including a base, and a finger body projecting from the base and slotted to receive the bar for supporting the finger thereon and means upon the frame adapted to coact with the bar for locking the bar in elevated position with the guard fingers retracted or locking the bar in lowered position with the guard fingers extended.

15 7. A device of the character described including a supporting frame, means for connecting the frame with the blade of a razor to extend longitudinally of the said blade, a longitudinal guard finger bar slidably supported by the frame, a series of guard fingers carried by the bar, and a swinging catch member mounted upon the frame and adapted to coact with the said bar for locking the bar in elevated position with the guard fingers retracted or for locking the bar in lowered position with the guard fingers extended.

20 11. A device of the character described including a supporting frame, means for connecting the frame with the blade of a razor to extend longitudinally of the said blade, a longitudinal guard finger bar supported by the frame, a series of guard fingers carried by the bar and each including a base, and means engaging the bases of the said fingers and connecting the fingers with the bar for adjustment thereon.

25 12. A device of the character described including a supporting frame, means for connecting the frame with the blade of a razor to extend longitudinally of the said blade and having the frame adjustable thereon whereby the frame may be positioned toward or away from the cutting edge of the

30 blade, a guard finger bar carried by the frame, and a series of guard fingers individually adjustable upon the said bar.

35 12. A device of the character described including a supporting frame, means for connecting the frame with the blade of a razor to extend longitudinally thereof, an arm extending from the frame at its inner end, a head piece connected to the frame at its outer end, a longitudinal guard finger bar 80 extending between said arm and head piece and slidably supported thereon, a series of guard fingers carried by the bar, and means upon the frame to coact with the bar for locking the bar in either elevated or lowered 85 position.

40 45 In testimony whereof I affix my signature.

CECIL ARTHUR HUBBARD. [L. S.]
